MULTIPLE CONTROL PANEL UNIT

John G. Booth, Fox Chase Manor, and Loren R. Davis, Newtown, Pa., assignors, by mesne assignments, to Minneapolis-Honeywell Regulator Company, Minneapolis, Minn., a corporation of Delaware

Application May 31, 1947, Serial No. 139,382

Term of patent 14 years

(Cl. D52—1)

To all whom it may concern:

Be it known that we, (1) John G. Booth and (2) Loren R. Davis, citizens of the United States, residing at (1) Fox Chase Manor, in the county of Philadelphia and State of Pennsylvania and (2) Newtown, in the county of Bucks and State of Pennsylvania, have invented a new, original, and ornamental Design for a Multiple Control Panel Unit, of which the following is a specification, reference being had to the accompanying drawing, forming part thereof.

Fig. 1 is a perspective view of the front of a multiple control panel unit, showing only the front panel section of the device of our new design.

Fig. 2 is a side elevation of Fig. 1; and

Fig. 3 is a bottom view of Fig. 1.

The dotted line showing in the drawing figures is for illustrative purposes only.

We claim:

The ornamental design for a multiple control panel unit, substantially as shown and described.

JOHN G. BOOTH.
LOREN R. DAVIS.
